UNITED STATES PATENT OFFICE

GEORGE W. LENTZ, OF CANTON, OHIO, ASSIGNOR, BY MESNE ASSIGNMENTS, TO REPUBLIC STEEL CORPORATION, OF YOUNGSTOWN, OHIO, A CORPORATION OF NEW JERSEY

APPARATUS FOR EXPANDING SLITTED METAL SHEETS

Application filed April 13, 1928. Serial No. 269,773.

This invention relates to improvements in machines for spreading or expanding slit metal sheets for the purpose of forming expanded metal lath and the like.

5 An object of the invention is to provide a rapid method of spreading a previously slit metal sheet to produce expanded metal lath of the herringbone, diamond, or other type.

10 A more specific object of the invention is to provide a cheap and efficient method of spreading or expanding a sheet which has been slit in accordance with the method described in the co-pending application of

15 Thomas A. Sindelar, Serial No. 269,820.

These and other objects of the invention will become more readily apparent in the course of the following description of the invention, taken in connection with the accompanying drawings, wherein

20 Fig. 1 is a side elevation of the spreader with the various parts thereof shown in the position they occupy at the beginning of the spreading operations;

25 Fig. 2 is a side elevation of the spreader with the various parts thereof shown in the position they occupy at the end of the spreading operation;

30 Fig. 3 is a front elevation of the left half of the spreader;

Fig. 4 is a front elevation of the right half of the spreader;

Fig. 5 is a cross-section through the spreader, taken on the line 5—5 of Fig. 4;

35 Fig. 6 is a cross-section through the spreader, taken on the line 6—6 of Fig. 1;

Fig. 7 is a cross-section, on an enlarged scale, through the rear clamping bars and adjacent portions of the spreader;

40 Fig. 8 is a cross-section, on an enlarged scale, through the front clamping bars of the spreader;

Fig. 9 is a cross-section through the cam and roller, taken on the line 9—9 of Fig. 2;

45 Fig. 10 is a cross-section, on an enlarged scale, through the conveyor mechanism;

Fig. 11 is a cross-section through the main and auxiliary drives, taken on the line 11—11 of Fig. 6.

50 Referring more particularly to the draw-

ings wherein like reference characters are used to designate like parts, it is seen that the machine consists essentially of seven major units, i. e., base, stationary clamping mechanism, movable clamping and shearing mechanism, conveyor mechanism, entrance table, exit table, and drive mechanism. Each of these major units will now be described in detail, and the method of operation of the machine as a whole will then be described.

Base

The base of the machine comprises I-beams 1, suitably spaced apart by means of angle cross-beams 2, and a channel 3. Bronze bearing plates 4 are secured to the upper flanges of the I-beams 1.

Stationary clamping mechanism

The stationary clamping mechanism includes an upper clamping bar 5 secured in a recess in bar holder 6, and a lower clamping bar 7 secured in a recess in bar holder 8. The bar holder 6 is in turn secured to cross-member 9, and bar holder 8 is secured to cross-member 10. The cross-member 9 is provided at its ends with bearing blocks 11 which are mounted to slide vertically in guides 12 of stationary housings 13 secured to I-beams 1. The ends of cross-member 10 rest upon shelves 14, integral with the housings 13, and are secured to the housings by means of clip angles 15.

For the purpose of facilitating insertion of the sheet to be expanded into the machine, pressure plate 16 is provided, this plate being mounted on a plurality of coil springs 17 for reciprocal movement in recess 18 of bar holder 8. The top of the pressure plate is beveled as at 19 to further facilitate entrance of the sheet.

Movable clamping and shearing mechanism

The movable clamping and shearing mechanism includes an upper clamping bar 20 secured in a recess in bar holder 21, and a lower clamping bar 22 secured in a recess in bar holder 23. The bar holder 21 is in turn secured to cross-member 24, and the bar holder 23 is secured to cross-member 25. The cross-

member 24 is provided at its ends with bearing blocks 26 which are mounted to slide vertically in guides 27 of movable housings 28. The ends of cross-member 25 rest upon shelves 29 integral with the housings 28 and are secured to the housings by means of clip angles 30.

A plurality of gauges or stops 31 mounted on coil springs 32 for reciprocal movement 10 in recess 33 of bar holder 23 are secured at their rear portions to an angle bar 34, this bar being in turn secured to arms 35 pivotally mounted at their rear ends on pins 36. Pins 36 are rigidly secured in the eyes 37 at the 15 ends of fulcrum arms 38, which are secured at their opposite ends to the web of cross-member 25.

The gauges further include eye-bolts 39 secured at one end to arms 35 by means of 20 links 40 and adjustably secured at their opposite ends in sleeves 41, the intermediate portion of the eye-bolts being adapted to reciprocate vertically in guide blocks 42 secured to the web of the cross-member 25. The 25 sleeves 41 are adjustably secured in boxes 43 having guide slots 44 extending therethrough.

The shearing mechanism, clearly shown in Fig. 6, includes two pairs of coacting rotary cutters 45 and 46, cutters 45 being adjustably 20 secured near the ends of arbor 47, and cutters 46 being adjustably secured near the ends of arbor 48. The reduced ends of the arbors 47 and 48 are mounted in bearing boxes 49, which are adjustably secured in guides 50 in 25 the movable housings 28. The arbor 47 is driven by the arbor 48 through the intermediary of gears 51 secured on the respective arbors.

Conveyor mechanism

40 The conveyor mechanism includes a plurality of coacting endless conveyor chains or belts 52, preferably of the link-belt type, mounted on sprockets 53 which are in turn 45 mounted on shafts 54 and 55, secured in suitable housings 56. The housings 56 are secured in stationary housings 13.

The sprockets 53 are driven through the 50 intermediary of gears 57 keyed to rear shafts 54 and 55. Pivottally secured at intervals along the rear shaft 54 at points spaced to correspond with the conveyor chains 52, are drag weights 58, which serve to take the slack 55 out of the upper conveyor chains, and thereby afford a better contact between the conveyor chains and the sheet to be expanded.

At spaced points intermediate the conveyor chains 52 are upper guides 59 secured 60 to and depending from an angle cross-bar 60, which is in turn secured at its ends to housings 13 and 56. Lower guides 61, spaced to correspond with the upper guides 59 are secured to an angle cross-bar 62, which is in 65 turn secured at its ends to housings 13 and 56.

Entrance table

The entrance table consists of upper guides 63 and lower guides 64. The upper guides 63 are secured at spaced intervals to an angle cross-bar 65, whose ends are in turn secured to housings 13. The lower guides 64 are spaced at intervals to correspond with the upper guides and are secured at their rear ends to an angle cross-bar 66, whose ends are in turn secured to housings 13. The front ends of the lower guides are secured to an angle cross-bar 67 which is in turn secured to the upper ends of upright angle legs 68, the lower ends of which are secured to an angle cross-bar 69 mounted on I-beams 1.

Exit table

The exit table consists of spaced angle bar guides 70 secured to angle cross-bars 71 and 72, the crossbars 71 being mounted on upright angle legs 73, and the cross-bars 72 being mounted on upright angle legs 74, whose lower ends are secured to channel 3.

Hold-down bars 75 having notches 76 intermediate their ends are secured at their ends to angle cross-bar 62 and upright angle legs 74. The hold-down bars pass through the guide slot 44 in boxes 43, and through slots 77 extending through boxes 78 secured to the lower flanges of cross-member 25.

Driving mechanism

A stub shaft 79 mounted in a miter bearing 80 secured to I-beam 1, is driven by a motor 81 through the intermediary of a gear reduction unit 82. A link-belt sprocket 83 is secured to the shaft 79 and serves to drive the rear conveyor shaft 55 through the intermediary of a link-belt chain 84.

Keyed to the end of shaft 79 is a miter gear 85 which serves to drive a shaft 86 through the intermediary of miter gear 87, keyed to the shaft 86. The shaft 86 is mounted at its front end in miter bearing 80, and at its rear end in bearing 88. Longitudinal movement of the shaft 86 is prevented by means of miter gear 87 and a collar 89 secured to the opposite end of the shaft. The shaft 86 is provided on diametrically opposite sides with splines 90 extending from the miter bearing 80 to the bearing 88.

Slidably mounted on the shaft 86 and prevented from rotating by the splines 90 are sleeves 91 and 92. A bearing 93 is secured at its upper portion to the movable housing 28, and encloses sleeves 91 and 92. A stub shaft 94 is mounted intermediate the ends of the bearing 93 and is driven by means of a miter gear 95, keyed to one end of sleeve 91, through the intermediary of miter gear 96 keyed to one end of the stub shaft. A link-belt sprocket 97 keyed to the opposite end of the stub shaft serves to drive the shearing mechanism through the intermediary of a

120

125

130

link-belt 98 and a link-belt sprocket 99 keyed to the arbor 48.

A shaft 100 is mounted in bearings 101 and 102 secured to the webs of I-beams 1, and is driven by means of a gear 103 mounted on shaft 100, and a pinion 104 mounted on stub shaft 79.

A clutch 105 of the non-repeating pin type is suitably mounted on one end of shaft 100 and is intermittently operated by means of foot pedal mechanism, as is usual in machines of this type. A cam-shaft 106 is mounted on bearings 107 which are integral with the stationary housings 13, and is driven through the intermediary of a pinion 108 and a clutch gear 109. The cam-shaft 106 is provided at both ends with internal cams 110, and since the reciprocating mechanisms on both sides of the machine are alike, only that on one side will be described.

A lever arm 111 is pivotally mounted on a bracket bearing 112 secured to the web of I-beam 1, and is provided at its opposite end with a roller 113 and a stud 114. Pivotally secured intermediate the ends of the lever arm 111 is a clevis 115 to the upper end of which a rod 116 is adjustably secured. The opposite end of rod 116 is secured to a bearing 117 which is in turn pivotally mounted on bearing block 11 by means of a stub 118. Pivotally secured on the outer face of cam 110, by means of a stud 119, is a bearing 120, to which is adjustably secured one end of a rod 121, the opposite end of the rod being secured to a yoke bearing 122. The yoke bearing is in turn pivotally secured to toggle lever arms 123 and 124. Lever arm 123 is pivotally secured to housing 28 by means of a stud 125 and lever arm 124 is pivotally secured to bearing block 26, by means of a stud 126.

Method of operation

With the various parts of the machine in the relative position shown in Figs. 1, 5, 7, and 8, a metal sheet of predetermined length and width, which has been slitted preparatory to expanding same, is placed upon the entrance table and inserted between upper and lower guides 63 and 64. It is then pushed over pressure plate 16 to a position where it may be carried rearward by the conveyor chains 52. The sheet is supported during this movement by guides 61, and moves rearward to stops or gauges 31.

The machine operator then presses the pedal mechanism, which is provided for the operation of clutch 105, whereupon the cam shaft 106 and cams 110 rotate; the right side cam 110, as shown in Figs. 1, 2, and 4 rotating in a clockwise direction. The groove in cam 110 acting on roller 113 depresses lever arm 111, thereby moving clamping bar 5 downward to securely clamp the forward edge of the sheet between it and the clamping bar 7.

The clamping action of bars 5 and 7 produces a marginal rib at the edge of the sheet at an angle of approximately 45 degrees with the plane of the sheet.

Simultaneously with the clamping action of bars 5 and 7, stud 119 moves in a clockwise direction with cam 110, thereby forcing bearing 120, rod 121, and yoke bearing 122 rearwardly. The rearward movement of yoke bearing 122, acting upon toggle lever arm 123 causes the latter to pivot on stud 125, and pulls upper clamping bar 20 downward to clamp the rear edge of the sheet between it and clamping bar 22. The clamping action of bars 20 and 22 produces a marginal rib at the edge of the sheet, at an angle of approximately 45 degrees with the plane of the sheet, and on the opposite side thereof from the rib at the other edge of the sheet.

The downward movement of clamping bar 21 forces gauges 31 downward, and boxes 43 thereby move downward to bring the lower surface of guide slots 44 to a position clear of the notches 76 in hold-down bar 75.

The entire movable clamping mechanism is then moved rearwardly to the position shown in Fig. 2 by the continued motion of bearing 120, rod 121, and yoke bearing 122, carrying with it the clamped rear edge of the sheet to thereby fully expand same.

Continued rotary motion of cam 110 reverses the movement of bearing 120, rod 121, yoke bearing 122, and toggle lever arm 123, and thereby releases the clamped edges of the sheet from the clamping mechanisms. Continued motion of the toggle lever arm 123 in a forward direction brings the lower portion of the rear face of this lever arm into contact with a stop 127 integral with movable housing 28. The entire movable clamping mechanism then moves forwardly.

During the expansion of the sheet, gauges 31 are held downward by hold-down bars 75, and the hold-down action is continued until the return of the movable clamping mechanism to the position shown in Fig. 1, the gauges then occupying the position shown in Figs. 5 and 7.

At the instant the clamped edges of the sheet are released, the conveyor chains 52 carry the sheet rearward to a position where the sheet may be sheared to predetermined length by means of rotary cutters 45 and 46.

The expanded and sheared sheet then passes on to the exit table from which it is removed by an assistant operator.

Obviously, many changes may be made from the details set forth without departing from the scope of the invention as defined in the appended claims.

I claim:

1. In a machine for expanding slitted metal sheets, means for gripping one edge of a sheet to be expanded, means for gripping the opposite edge of the sheet, gauges associated

- with one of said gripping means to limit the movement of the sheet into the machine so that its edges are in proper position to be gripped by said gripping means, means for moving one of said gripping means away from the other to expand the sheet and means adapted to hold the gauges out of the path of the sheet after the expanding operation in order to permit passage of the expanded sheet out of the machine.
2. In a machine for expanding slitted metal sheets, means for gripping one edge of a sheet to be expanded, means for gripping the opposite edge of the sheet, conveyor means disposed between said gripping means and means for moving one of said gripping means away from the other to expand the sheet.
3. A structure as defined in claim 2, in which said conveyor means comprises endless chains.
4. In a machine for expanding slitted metal sheets, two pairs of gripping bars for the opposite edges of a slitted sheet shaped to bend the edges at similar inclinations on opposite sides of the plane of the sheet, means for feeding the sheet into the machine, means for stopping the sheet in proper position to be gripped by said bars, means for moving one pair of bars away from the other pair to expand the sheet, and means for feeding the expanded sheet out of the machine.
5. In a machine for expanding slitted metal sheets, means for feeding a slitted sheet into the machine, pairs of bars for gripping the opposite edges of the sheet, vertically movable stop devices for stopping the feeding movement of the sheet when its edges are in proper position for being grasped by said gripping bars, means for separating the pairs of bars to expand the sheet, means for retracting the stop devices and means for holding the stop devices in retracted position while the expanded sheet is being fed out of the machine.
6. In a machine for expanding slitted metal sheets, a pair of gripping bars for engaging and holding the rear edge of a slitted sheet, a pair of gripping bars for engaging the front edge of the sheet, feed chains arranged between the pairs of bars to lightly engage the upper and lower surface of the slitted sheet and means for moving one pair of bars away from the other pair of bars to expand the sheet, said chains permitting the sheet to expand and slip relatively thereto and serving to feed the slitted sheet into position for expansion and also serving to feed the expanded sheet partially out of the machine.
7. In a machine for expanding slitted metal sheets, clamping means for holding the rear edge of a slitted sheet, clamping bars for grasping the front edge of the sheet, means for moving said clamping bars away from said clamping means for expanding the slitted sheet, means for feeding the sheet between the clamping means and clamping bars and a pair of rotary cutters for automatically shearing at least one end of the expanded sheet as it is fed from the clamping bars.
8. In a machine for expanding slitted metal sheets, clamping means for holding one edge of a slitted sheet, clamping bars for grasping the opposite edge of the sheet, means for moving the clamping bars away from the clamping means to expand the slitted sheet, means for feeding the expanded sheet partially out of the machine after the expanding operation and rotary cutters for automatically shearing at least one end of the expanded sheet as it is fed out of the machine.
9. In a machine for expanding slitted metal sheets, clamping bars for grasping the opposite edges of a slitted sheet, continuously moving means for feeding sheets to and from said clamping bars, means for intermittently actuating said clamping bars to engage and expand the slitted sheets and continuously rotating shearing means for trimming the ends of the sheets as they leave the clamping bars.
10. In a machine for expanding slitted metal sheets, means for holding one edge of a slitted sheet stationary, means for grasping and pulling the opposite edge of the sheet to expand the sheet, said means including movable housings, arbors carried by and movable with said housings and rotating shearing cutters carried by said arbors for trimming the sheet and means for feeding the expanded sheet to said cutters.
11. In a machine for expanding slitted metal sheets, a pair of holding bars, means for guiding a slitted sheet between said bars, means for pressing one bar toward the other to grasp the rear edge of the sheet, mechanism for feeding and expanding the sheet away from said holding bars, said mechanism including two pairs of sprockets and connecting chains arranged respectively above and below the sheet for feeding the sheet, and means for shearing the sheet, said shearing means acting on the sheet automatically as it is fed forward after the rear edge is released from the pressing means.
12. In a machine for expanding slitted metal sheets, a pair of upper and lower holding bars, one of which is movable up and down to coact with the other to clamp and hold the rear edge of a slitted sheet stationary, housings movable toward and from said holding bars, a pair of upper and lower pulling bars carried by and movable back and forth with said housings, one of said pulling bars being movable up and down in said housing to coact with the other and grasp the front edge of the sheet, mechanism for sequentially bringing the bars of the respec-

tive pairs into clamping relation and then expanding the slotted sheet, means for feeding the sheet between the pairs of bars and means carried by the housings and movable therewith for feeding the expanded sheet away when it is released.

13. In a machine for expanding slotted metal sheets, a pair of stationary housings, a lower holding bar, a clamping bar mounted in said housing above the lower bar and vertically movable to coact with the lower bar, a horizontally movable pair of housings, lower and upper gripping bars carried by and movable horizontally with said latter housings, the upper gripping bar being vertically movable in said movable housings, a transverse shaft, a cam and a crank connected to said shaft, operating connecting means between said cam and said vertically movable clamping bar, toggle arms carried by said horizontally movable housing, a stop on said housing for one of said arms, one of said arms being connected to the upper gripping bar to move it up and down and a rod connecting said toggle arms and said crank.

In testimony whereof I affix my signature.

GEORGE W. LENTZ.
